US0D1049424S

(12) **United States Design Patent** (10) **Patent No.:** **US D1,049,424 S**
(45) **Date of Patent:** **** Oct. 29, 2024**

(54) **SEQUENCING INSTRUMENT**

(71) Applicant: **Illumina, Inc.**, San Diego, CA (US)
(72) Inventors: **Erik Allegoren**, San Diego, CA (US);
Erik Williamson, San Diego, CA (US);
Jack Godfrey Wood, San Diego, CA
(US)

(73) Assignee: **Illumina, Inc.**, San Diego, CA (US)

(**) Term: **15 Years**

(21) Appl. No.: **29/867,635**

(22) Filed: **Nov. 1, 2022**

(57) **CLAIM**

The ornamental design for a sequencing instrument, as shown and described.

DESCRIPTION

FIG. 1 is a front, top left perspective view of a sequencing instrument, illustrating our new design;

FIG. 2 is a rear, bottom left perspective view of the design of FIG. 1;

FIG. 3 is a front elevational view of the design of FIG. 1; FIG. 4 is a rear elevational view of the design of FIG. 1; FIG. 5 is a left side elevational view of the design of FIG. 1;

FIG. 6 is a right side elevational view of the design of FIG. 1;

FIG. 7 is a top plan view of the design of FIG. 1; and, FIG. 8 is a bottom plan view of the design of FIG. 1.

The broken lines shown in the drawings illustrate portions of the sequencing instrument that form no part of the claimed design.
